UNITED STATES PATENT OFFICE

111,051

DESIGN FOR A FUR TOPPER

Bernard Reineman, New York, N. Y.

Application May 27, 1938, Serial No. 77,423

Term of patent 3½ years

To all whom it may concern:

Be it known that I, Bernard Reineman, a citizen of the United States of America, residing in New York city, in the Borough of Manhattan, county and State of New York, have invented a new, original, and ornamental Design for a Fur Topper, of which the following is a specification, reference being had to the accompanying drawing, forming part thereof, wherein,

Figure 1 is a front view of a fur topper showing my new design.

Figure 2 is a rear view of the fur topper shown in Figure 1.

My design comprises a sleeveless fur topper consisting of a waistlength back, a collar and a two-panelled front extending below the waistline, said front having a narrow belt which continues from each side of the back as shown.

I claim:

The ornamental design for a fur topper, substantially as shown and described.

BERNARD REINEMAN.
